UNITED STATES PATENT OFFICE.

JOHN C. WILHELM, OF SHAVER'S CREEK, PENNSYLVANIA.

IMPROVEMENT IN GAME APPARATUS.

Specification forming part of Letters Patent No. **145,706**, dated December 16, 1873; application filed November 8, 1873.

To all whom it may concern:

Be it known that I, JOHN C. WILHELM, of Shaver's Creek, in the county of Huntingdon and State of Pennsylvania, have invented a new and valuable Game of Intellectual Amusement and Skill; and I do hereby declare that the following is a full, clear, and exact description of the construction and operation of the same, reference being had to the annexed drawings, making a part of this specification, and to the letters and figures of reference marked thereon.

The figures of the drawing show a representation of a plan view of my game-board and pieces.

This invention has relation to a parlor or indoor game of skill of the class which is generally played by two players with movable pieces or men upon a checkered board, in the manner of chess, drafts, and other games of like character; and it consists in the novelty of the construction, arrangement, and moves of the pieces, and of the system of the game, as hereinafter more fully set forth.

The pieces generally have republican names of office, and are, therefore, better adapted for the amusement of the leisure hours of the people of a free country than those of chess or other games where the pieces are known by titles of royalty and its appendages.

In the accompanying drawings, the letter A indicates the checkered board, having ten squares each way, or one hundred squares in all. The pieces are arranged upon the four lines of squares nearest the opposite edges B B' of the board, in the manner hereinafter described.

Each player is provided with forty-eight pieces, as follows: Forty original, including a president, *a*, indicated by a shield or other suitably-formed piece; a capitol, *b*, or miniature domed building; a flag, *c*; a general or star-shaped piece, *d*; two trains or wheel-shaped pieces, *e*; two admirals or anchor-shaped pieces, *f*; two ships, *g*; two monitors, *h*; two cavalrymen or horse-shaped pieces, *i*; four artillerymen or canon-shaped pieces, *k*; two forts, *l*; and twenty militiamen or pawn-shaped pieces, *m*. Eight promoted pieces, including a veteran or chevron-shaped piece, *n*; a sergeant or diamond-shaped piece, *p*; a major or crossed-

swords piece, *q*; a colonel or crossed-cannon piece, *r*; an engineer, indicated by a field-glass, *s*; a quartermaster, indicated by a trefoil, *t*; a surgeon, indicated by a caduceus, *u*; and a chaplain, indicated by a cross, *v*.

The forty original pieces are, when the players commence, arranged upon the board in the following manner: At each end of the line nearest the player, or base-line, is placed a ship, next to each ship an admiral, and next to each admiral a train, leaving four inner squares, which are occupied, respectively, from the right, by the president, capitol, flag, and general. The pieces on the second line are arranged as follows: In front of the ships, at each end, are the monitors, next the cavalrymen, and next two artillerymen, one in front of each train; next are placed the forts, and next to these the other two artillerymen, which thus occupy the two inner squares in front of the capitol and flag. The third and fourth lines are occupied by militiamen. The promoted pieces are not all upon the board in the original arrangement. More than one of each of the promoted pieces may be required.

The following is the explanation of terms:

Base—The rear line of squares next each player.

Ocean—The outer row of squares at either flank.

Coast-line—The row of squares next the ocean.

Infantry—Militiamen, veterans, and sergeants.

Mounted forces—Cavalry, artillery, major, colonel, and general.

Naval forces—Monitors, ships, and admirals, supplies, trains, and ships, and forts in communication with a train or a ship.

Non-combatants—Pieces which do not effect captures, to wit, the capitol, the president, the flag, the trains, the engineer, quartermaster, surgeon, and chaplain.

Direct—Not diagonally.

Zigzag—Back and forth on two rows of squares alternately, direct or diagonally.

Under fire—Liable to capture at the next move.

In conjunction—Occupying squares which touch each other by a side or angle.

In communication—Capable of being

brought into conjunction by one move of either piece.

Protected—Secured from capture by conjunction with certain other pieces.

The following are the movements of the pieces:

Militiamen—Diagonally forward one square.

Veteran—Diagonally forward or backward one square.

Sergeant—Direct one square.

Major—Direct or diagonally one square.

Colonel—Diagonally one or two squares.

Artillery—Direct one or two squares.

Cavalry—Two squares, one direct and one diagonally.

Fort—Direct or diagonally one or two squares, not on the ocean.

Monitor—One, two, or three squares direct on the ocean, or zigzag on ocean and coast-line.

Ship—Direct any distance on the ocean.

Non-combatants—Direct or diagonally one or two squares.

Admiral—As a monitor, ship, or colonel.

General—As any other piece whatever.

No piece except supplies can move over the boundary line, which is the middle line between the opposing parties, beyond communication with supplies.

Any two pieces mutually movable to each other's squares can, as one move, exchange places, but not over the central line, which is the middle line of the board at right angles with the boundary-line.

All pieces moving more than one square can move over pieces of their own color, but not over an enemy.

The first move for the first game is determined by lot; afterward it belongs to each player alternately.

Either player may at any time decline to move; but if the other also declines, he must then move, or it is a drawn game.

If a player touch a piece without notifying his antagonist of a purpose other than to move it, he may be compelled to move it, and a piece once set down may be required to remain.

If there be two players upon a side, each moves only the pieces on his own side of the central line. He may move a piece from his side across the central line, but not the reverse.

The laws of capture are as follows: Artillery, forts, and vessels, without moving, capture any piece within two squares direct, or one square diagonally. Other combatant pieces capture by displacement—that is to say, they take the pieces to whose squares they move. No piece can be captured which is protected. When any piece is left beyond

communication with supplies, it is liable to capture as if under fire. Only one piece can be captured at one time, each capture counting as a move, except when made by displacement. In this case the move and capture count as one. The game is won by the capture of the flag and capitol.

The powers of protection of the pieces are as follows: A sergeant protects infantry; a major protects cavalry and artillery; a colonel protects mounted forces; an admiral protects naval forces; the general protects the flag and all combatants; the president protects all pieces; the flag and capitol mutually protect each other; the engineer protects artillery, forts, vessels, and the capital; the quartermaster protects supplies; the chaplain and surgeon protect infantry, cavalry, artillery, and all officers. A piece under fire or beyond supplies cannot protect another, unless it be itself protected by a piece which is in supply and not under fire. No piece can protect another not in conjunction with it.

Pieces are promoted as follows: Militiamen penetrating the enemy's base-line become veterans; militiamen capturing superior infantry become sergeants; infantry capturing cavalry or artillery become majors; infantry capturing a major, colonel, or general may be made a colonel; infantry capturing a fort or the capitol may be made an engineer; infantry capturing a source of supply may be made a quartermaster; infantry capturing a vessel may be made an admiral; infantry capturing a president or any non-combatant officer may be made a chaplain; infantry capturing a flag, general, or admiral may be made a surgeon.

There cannot be of the same rank and color at the same time more than one non-combatant officer, or more than two combatant officers, one on each side of the central line.

Promotions, except to veterans, may be dispensed with, or they may be confined to infantry or combatants, according to the proficiency or pleasure of the players.

Promotions, if made, must be made immediately as they are merited, before the opposing player has moved.

What I claim as new, and desire to secure by Letters Patent, is—

The game apparatus herein described, consisting of the board and pieces, substantially as and for the purpose specified.

In testimony that I claim the above I have hereunto subscribed my name in the presence of two witnesses.

JNO. C. WILHELM.
